UNITED STATES PATENT OFFICE

ALPHONSE DOLLFUS, OF PHILADELPHIA, PENNSYLVANIA.

CORKING-MACHINE.

SPECIFICATION forming part of Letters Patent No. 602,837, dated April 26, 1898.

Application filed August 17, 1897. Serial No. 648,501. (No model.)

To all whom it may concern:

Be it known that I, ALPHONSE DOLLFUS, a citizen of the United States, residing at Philadelphia, in the county of Philadelphia and 5 State of Pennsylvania, have invented a certain new and useful Improvement in Corking-Machines, of which the following is a specification.

My invention relates to a new and useful improvement in machines for corking bottles and the like, and has for its object to provide a simple and effective device of this description which may be operated by hand and adjusted to various heights of bottles within its 15 limit and by means of which a cork may be quickly and conveniently forced within a bottle with but little care upon the part of the manipulator; and a further object of my invention is to provide a gage whereby each 20 cork may be forced within its bottle to an exact distance, and this regardless of the height of the bottle; and a still further object of my invention is to provide means for holding the adjustable bracket in any position.

With these ends in view this invention consists in the details of construction and combination of elements hereinafter set forth, and then specifically designated by the claims.

In order that those skilled in the art to which this invention appertains may understand how to make and use the same, the construction and operation will now be described in detail, referring to the accompanying drawings, forming a part of this specification, in which—

Figure 1 is a side elevation of my improvement, showing a bottle in position prior to being corked; Fig. 2, a vertical section showing the plunger forced downward in driving a cork within the bottle, and Fig. 3 a plan view of the machine.

In carrying out my invention as here embodied, A represents the base of the machine, 45 which is of sufficient size and proper design for supporting the machine and the bottles to be corked, and B is a standard projecting upward from this base and having guideways C formed upon the edges of the upper portion thereof, around which the sections of the bracket D are secured. This bracket, being 50 thus secured around the upper portion C of

the standard, is adapted to slide vertically thereon, and a series of teeth E are formed with the standard with which the pinion F 55 meshes, said pinion being secured upon the spindle G, journaled in the rear portion of the bracket. A hand-wheel H is secured upon the spindle, and by the revolving of said wheel it will be seen that the pinion will cause 60 the bracket to move up or down, as the case may be, and to prevent the bracket from falling from any adjustment to which it may be placed a spring I is coiled about the spindle between the hub of the hand-wheel and the 65 rear portion of the bracket, and the tension of this spring will produce sufficient friction upon the hub of the hand-wheel to retard the rotation of the spindle sufficiently to hold it against the tendency of the bracket to move 70 downward. The head J of the bracket has formed therein the guideways K, and between these ways is fitted the plunger-bar L, so as to slide vertically, and having formed thereon the teeth M, with which meshes the 75 segmental gear N, the latter being journaled at O within the head and having formed therewith or secured thereto the operating-handle P, by which arrangement the plunger-bar may be moved up and down, as described, as 80 will be readily understood. The lower end of the plunger-bar has formed therein a socket for the reception of the plunger Q, and this plunger is held in place by the set-screw R. A cylindrical housing S is formed with the 85 lower portion of the bracket and has fitted therein a bushing T, said bushing being flared upward for the reception of a cork, while the housing is flared at its lower end, as indicated at U, for fitting over the head of the 90 bottle V. A clamp-screw W serves to bind the bushing in place within the housing, and this bushing may be removed and another substituted therefor with a different sized opening therein for the accommodation of 95 different sized corks, and it is obvious that a series of these bushings being provided for each machine a large variety of sizes of corks may be manipulated thereby.

X represents a lug formed upon the side of 100 the head of the bracket, and has threaded therethrough the gage-screw Y, against which the operating-handle P strikes when moving downward, thereby limiting said handle, and

as this screw may be adjusted it is obvious that the downward limit of the handle may be varied to suit the requirements of the work in hand.

5. From this description it is obvious that in practice a bottle may be placed upon the base A after the bracket has been elevated, so as to carry the housing above the top of said bottle, and by manipulating the hand-wheel H the housing will be caused to fit over the head of the bottle and the bushing brought in contact therewith, after which a cork, being placed within the flared opening in the bushing, may be quickly forced within the bottle to the exact depth desired by the downward movement of the plunger-bar through the medium of the operating-handle, as before described. After the gage-screw Y has been adjusted so as to carry the plunger to the proper distance below the bushing it will be seen that regardless of the height of the bottle each cork will be forced home to the same distance, since the bushing, resting upon the head of the bottle, forms a gage for the starting-point of the cork, and as the plunger is carried by the bracket its downward movement will always be the same relative to the bushing, which is also carried by said bracket. When the cork has been forced home, a slight reverse movement of the hand-wheel H will elevate the bracket above the level of the bottle, thereby permitting a free removal of said bottle and the substitution therefor by another, and the proper movement of the plunger will permit the insertion of a new cork, when the operations just described may be repeated with a like result.

By the use of my improvement large numbers of bottles may be quickly and advantageously corked, thus saving considerable time and labor and accomplishing the work in a superior manner with less skilled help.

The cost of manufacturing a machine of this description is exceedingly small, since the principal parts thereof are made of cast-iron and require but little machine-work for their assembly.

Having thus fully described my invention, what I claim as new and useful is—

50. 1. A machine for corking bottles consisting of a base, a standard projecting upward therefrom, guideways formed upon the upper portion of said standard, a series of teeth formed upon this upper portion, a bracket adapted to slide upon the guideways, a spindle journaled in the rear portion of the bracket, a pinion carried by said spindle and meshing with the teeth, a hand-wheel for revolving the spindle, a spring for retaining the spindle against accidental rotation, a

plunger-bar fitted to slide vertically in the bracket, teeth formed upon said plunger-bar, a segmental gear journaled in the bracket and meshing with the last-named teeth, an operating-handle formed with the segmental gear, a plunger carried by the plunger-bar, a housing formed with the bracket, and a flared bushing fitted within the housing, substantially as and for the purpose set forth.

2. In combination, a base, a standard, guideways formed upon said standard, teeth E also formed upon the standard, a bracket adapted to slide upon said ways, a pinion meshing with the teeth, means for operating said pinion, a plunger-bar, teeth M formed upon said bar, a segmental gear meshing with the last-named teeth, an operating-handle formed with the segmental gear, a gage-screw carried by the bracket and adapted to limit the downward movement of the operating-handle, a plunger detachably secured within the plunger-bar, a housing formed with the bracket, and a bushing having a flared opening therethrough secured within the housing, all arranged substantially as and for the purpose set forth.

3. A machine for corking bottles consisting of an upright standard, guideways formed on the upper portion thereof, a series of teeth also formed on said upper portion, a bracket adapted to slide on the guideways, a spindle journaled in the rear portion of the bracket, a pinion carried by said spindle meshing with the teeth, a hand-wheel for operating the spindle, a spring for retaining the spindle against accidental rotation, a plunger fitted in the bracket to slide vertically and means for raising and lowering said plunger independently of the bracket, substantially as set forth.

4. In a corking-machine, a bracket, a plunger-bar slidable vertically therein, a plunger secured to the plunger-bar, a rack-bar formed on the plunger-bar, a segmental gear journaled in the bracket meshing with said rack-bar, a handle on the gear, a lug on the side of the bracket, a set-screw threaded therethrough to strike the handle, a supporting-standard on which the standard is slidably mounted, and means for raising and lowering the bracket and holding it in position, substantially as set forth.

In testimony whereof I have hereunto affixed my signature in the presence of two subscribing witnesses.

ALPHONSE DOLLFUS.
